UNITED STATES PATENT OFFICE.

FRANCES WRIGHT, OF NEW YORK, N. Y., ASSIGNOR TO THE BUTTERICK PUBLISHING COMPANY, (LIMITED,) OF SAME PLACE.

DESIGN FOR A CHILD'S COSTUME.

SPECIFICATION forming part of Design No. 15,106, dated June 24, 1884.

Application filed May 12, 1884. Term of patent 23 years.

To all whom it may concern:

Be it known that I, FRANCES WRIGHT, of the city, county, and State of New York, have invented and produced a new and original Design for a Pattern of a Child's Costume, (numbered 9,212;) and I do hereby declare that the engraved prints accompanying this specification convey to any one accustomed to using paper patterns a clear understanding of how to a garment made up by the pattern will appear.

The design shows a round skirt and a jacket. The jacket exhibits short loose-fitting fronts, that flare from the throat over narrow deeper

vest portions, exhibiting a fastening all the way down, a half-lifting back filling in points at the lower edge, coat-sleeves, and a standing collar.

What I claim as my invention, and desire to secure by Letters Patent, is--

The design for a child's costume, as shown in the engraved prints accompanying this specification.

FRANCES WRIGHT.
